UNITED STATES PATENT OFFICE.

JAMES C. GINTER, OF SAN GABRIEL, CALIFORNIA.

BRAKE EQUALIZER.

Application filed April 7, 1924. Serial No. 704,719.

This invention relates generally to winches or hoisting drums provided with braking means for checking their rotation. It is particularly concerned, in certain of its aspects, 5 with winches having a plurality of brake drums adapted to be actuated by a common operating means for simultaneously engaging a plurality of cooperating brake drums.

While the invention may be embodied in 10 many different forms and used in various situations, it is particularly applicable to hoisting apparatus used in connection with the drilling of oil or artesian wells. Therefore I have illustrated and will describe the 15 invention as applied to this particular use, but this is not intended as an implication that the invention is in any way limited to such specific application.

Again, considering only the well drilling 20 art, the invention may be applied with equal advantage either to "standard" or "rotary" drilling rigs, but I will confine this description to a "draw works" installation wherein a winch or hoisting drum is utilized for raising and lowering drill or well pipe, fishing tools, etc.

Tools and well pipe are lowered and raised 25 through a well bore by a cable which is trained upwardly and over a crown block at the top of the derrick or rig, and then carried down to a power driven winch. The drill pipe or casing is first set up on the derrick floor in "stands," each stand consisting of several lengths of pipe coupled end to end.

30 By means of an elevator carried by the hoisting cable, the first stand is picked up from the floor and allowed to gravitate into the hole by giving the hoisting drum freedom of rotation. The speed of gravitation is controlled by the simultaneous application of 35 braking force on the two brake drums with which the winch is provided, and the stand is finally brought to rest with its upper end protruding from the top of the well, by completely braking the winch. Thereupon, 40 "slips" are utilized to hold the stand while the elevator is released therefrom to pick up another stand which is subsequently coupled to the first. The slips are then removed and

45 the two stands lowered, this process being continued until the entire "string" is lowered. Of course, the weight of cable supported pipe increases directly as stands are added to the string, and when it is considered that there

may be several thousand feet of pipe to be 55 lowered, say, eighty feet each time a stand is added, and the vertical movement of the casting controlled and checked solely by braking the drum, it is obvious that a very considerable amount of heat is generated between 60 brake drum and band, and that the wear and tear on the brake bands or their lining is very great.

These severe service conditions are aggravated by reason of the fact that in the usual 65 type of winch it is impossible to exactly equalize the brakes, with the natural result that one brake is called upon to bear the brunt of the strain and receives much more wear than the other. This condition results in the 70 necessity of frequently replacing the lining of the brake band which is subject to excessive wear, not only a most expensive procedure from the standpoint of material cost and time lost, but requiring readjustment of 75 both brakes after each relining operation, since the new lining will be relatively thick while the partially worn lining of the other band is relatively thin. When it is remembered that the usual brake bands of a rig 80 winch are nine feet or more in length, it will be realized that the purchase price of a lining is, in itself, a very considerable item, and further that the time consumed in each relining operation is sufficient to materially affect the 85 ultimate cost of the well drilling operation, for the draw works and its crew must remain idle during periods of brake repair.

An unequal application of braking force 90 results in the existence of uneven heat conditions throughout the extent of the drum, and the consequent uneven expansion of the drum metal and the expansion of the air confined within the drum, causes strains to be set up 95 which have resulted in "drum explosions" on more than one occasion known to me, these explosions bringing about the loss of life and property.

Furthermore, the uneven application of 100 braking force tends to defeat one of the main purposes of providing a plurality of bands on each drum, for the major portion of the work must be accomplished through a single band, and the operator's control over the winch is accordingly limited to his efforts as 105 applied to a single brake drum.

Therefore, I have provided means for equalizing the brakes to render them equally

efficient and properly coordinated. My equalizer practically eliminates all the above mentioned objectionable features of usual winches.

5 Generally, I accomplish my purpose by substituting a yieldable connection for the usual rigid connection at one end of each brake band. This connection is a cylinder and piston arrangement and I provide a communicating duct between the two cylinders. The cylinders are preferably supplied with liquid which is placed under pressure between the two pistons during brake application, and it follows that the fluid pressure 10 in the two cylinders must come into equilibrium when the bands are contracted about their respective drums by movement of the common brake lever, with the result that the braking force on the several drums is applied 15 equally, irrespective of any differential in the clearance between the several bands and their drums prior to brake application.

The yieldable anchoring of the bands has further beneficial results in that it has a 20 cushioning effect, prevents "harsh" brake application, enables the driller to regulate the braking pressure more finely, and does not require a tense straining of the driller's arm to effect and maintain brake application. 25 This is true whether the connection be applied to a single brake band acting alone or to a plurality of bands acting together.

As a further feature, I introduce a gage 30 in the pressure line, the gage being calibrated in any suitable manner to indicate variable pressure, and by noting the variable pressure recorded when different work is supported by the hoisting cable, the gage serves as a weight indicator. This feature is of great value in 35 determining whether or not a tool has become twisted off, or whether or not a fishing tool has "picked up" a "lost" tool or section of drill pipe. For instance, when the driller has lowered the string to bring the drill into 40 operative position, he may lift and hold the string just off bottom and note the pressure indication of the gage. Should he later lift and hold the string and note that the gage indicates a drop in pressure, he is immediately warned that less force is required to 45 support the string, leading to the obvious conclusion that the string has parted and that a portion thereof has been left on bottom.

Conversely, in a fishing job an increased 50 weight indication serves to notify the driller that the "lost" tool has been caught by the fishing tool and has become attached to the string so it may be withdrawn.

Another instance of advantageous use of 55 weight indication, is in straight drilling, where the driller does not wish to allow the full weight of the string to bear on the drill. In such a case, he keeps constant pressure on the brakes, thus relieving the tool from a definite portion of the string weight and decreas-

ing the speed with which the cutting tool may sink through the work. Having determined the braking force necessary to relieve the tool to the proper or desired degree he may keep this force constant by such regulation of the 70 brakes as will maintain a constant gage indication.

Other features of novelty and objects of the invention will be set forth in the following detailed description, reference being had 75 to the accompanying drawings, in which

Figure 1 is a somewhat diagrammatic view of a drilling rig, showing a hoisting winch in connection therewith.

Fig. 2 is an elevation of a winch equipped 80 with my equalizer; and

Fig. 3 is a vertical section on line 3—3 of Figure 2.

In the drawings, the numeral 10 generally indicates a derrick on the platform or floor 85 11 of which is mounted a winch 12. Floor 11 may be considered as the base or supporting member of the winch which latter includes a cable winding drum 13 having brake drums 14 and 15. A shaft 16 is journaled in 90 bearings 17 on uprights 18 (which uprights may be the derrick columns) and serves to revolvably support the winch drum; and power from a suitable source (not shown) may be transmitted to shaft 16 through any 95 suitable drive connection.

Hoisting cable 19 is wrapped about the drum 13 and extends upwardly to the derrick top. It is then rove through crown block 20 and traveling block 21, the latter supporting 100 hook 22 from which the circulating head (not shown) or elevator 23 is suspended. Elevator 23 is removably attached to the uppermost length of pipe 24 which is to be lowered through the casing C within the well bore. 105 It is obvious that pipe 24 may be raised or lowered by taking up or paying out cable 19 through proper actuation of winch 12.

Brake bands 25 and 26, for drums 14 and 15, respectively, have the usual removably attached linings 27, and one end of each band is attached by clevis 28 to cranks 29 on shaft 30. Crank shaft 30 is journaled in the bearing 31 110 on floor 11 and is adapted to be rocked by brake lever 32.

The opposite end of each band has a clevis or attachment strap 33 through which are passed the bars 34 of U-bolts 35. Adjustably secured by nuts 36 to the lower extremities of the U-bolt legs are bridges 37 upon which pistons 38 and 39 are secured by bolts 40. In effect U-bolts 35 and bridges 37 combine to form longitudinally adjustable stirrups. 120

Pistons 38 and 39 are adapted to reciprocate within inverted cup cylinders 41 and 42, respectively, which cylinders have their upper ends closed by caps or end walls 43. The cylinders have lateral ears 45 which are pierced at 46 to allow the free passage of the U-bolt legs therethrough, and are adapted to 125 130

receive anchor bolts 47 extending upwardly from floor 11. Nuts 48 are threaded on bolt 47 above and below ears 45 and serve to support the cylinders in adjusted position with respect to the floor and pistons. Fluid 50 (heavy machine oil, for instance) is introduced to the pressure chamber 50^a of the cylinders (the chambers being defined by the walls and ends 48 of the cylinders and the tops of the pistons) in any suitable manner. I prefer to tap nipples 51 into the side walls of the cylinders for the purpose of so introducing the fluid. Oil cups 52 on the nipples serve to hold a reserve supply of fluid, the fluid flowing from cups to cylinders being controlled by shut-off valves 53. A pipe 54 extends from cylinder to cylinder, opening into each cylinder at a point above the limit of the piston's upstroke.

It is obvious that when lever 32 is swung in a counter-clockwise direction, as viewed in Figure 3, cranks 29 rock to the left, drawing bands 25 and 26 around respective drums and raising the pistons until the fluid in the pressure line is compressed to such an extent that further piston movement is retarded or checked, whereupon the bands contract about their drums to effect a braking of the winch. Due to the connecting pipe between the fluid or pressure chambers of the two cylinders, the fluid, in effect, is compressed between the two pistons and since the piston areas presented to the fluid in each cylinder are equal, the braking force as exerted by the two brake bands cannot be other than equal, all inequalities in original clearance between bands and drums being compensated by the equalizer.

Thus the pressure line in connection with the movable pistons, provides an efficient equalizer that insures equal wear on the brake band linings, even heating of the winch, etc., all to the end of producing the beneficial results and eliminating the objectionable features of other winches as outlined in the foregoing part of this specification.

To insure a snug and fluid tight fit between pistons and cylinders, pistons 38 and 39 may be provided with leather cup packings 55, piston rings, or the like.

As the brake linings wear away and thus allow a gradual increase in the piston stroke, it is preferable that the supply of oil in the pressure line be replenished through nipple 51. In the event sufficient air has leaked into the cylinders to resist entry of a new supply of fluid, one of the valves 53 may be opened to bleed off this air as the fluid flows in through the other valve. If there has been no air leakage, cups 52 are filled, both valves 53 are opened, and the pistons are depressed to draw in the replenishing charge of fluid.

In certain instances it is desirable to use only sufficient oil in the pressure line and fluid

chambers to provide a liquid seal between cylinders and pistons, and depend upon the compression of air in the pressure line to secure the equalizing effect.

By introducing gage 56 in the pressure line, the operator may be kept constantly advised as to the amount of fluid pressure existing during brake application, and the calibration of the gage may be such as will indicate that certain weights are capable of being fully supported by cable 19 when the gage hand stands at certain predetermined positions. As pointed out above, this knowledge may be used to advantage in determining whether or not the entire string of cable supported pipe remains intact, whether or not a lost tool or pipe section has been picked up by a fishing tool, and whether or not the full weight of the string bears on the drill.

It is to be understood that the drawings and description are merely illustrative of and not restrictive on the broader claims appended hereto, and various changes in structure, arrangement, and design may be made without departing from the spirit and scope of such claims.

I claim:

1. In a winch mounted on a support, a plurality of brake drums, a brake band for each drum, and a yieldable connection between the support and one end of each band; each of said connections including two members capable of telescopic movement and defining between them a pressure chamber, one of the members being anchored to the support, and the other member being connected to and movable with the band, means for regulating the telescopic stroke of the members; the pressure chambers of the several connections being in communication and adapted to confine a pressure transmitting medium; and force applying means adapted to act on the other end of each band to apply the bands to their respective drums.

2. In a winch mounted on a support, a plurality of brake drums, a brake band for each drum, and a yieldable connection between the support and one end of each band; each of said connections including two members capable of telescopic movement and defining between them a pressure chamber, a valved inlet for the chambers, one of the members being anchored to the support, and the other member being connected to and movable with the band; the pressure chambers of the several connections being in communication and adapted to confine a pressure transmitting medium; and force applying means adapted to act on the other end of each band to apply the bands to their respective drums.

In witness that I claim the foregoing I have hereunto subscribed my name this 29th day of March, 1924.

JAMES C. GINTER.
